UNITED STATES PATENT OFFICE.

PETER O. TERHEUN AND JOHN I. ACKERMAN, OF HOHOKUS, NEW JERSEY.

IMPROVEMENT IN MACHINES FOR CLEANING BOOTS AND SHOES.

Specification forming part of Letters Patent No. 130,829, dated August 27, 1872.

Specification describing a certain Device for Cleaning Boots and Shoes, invented by PETER O. TERHEUN and JOHN I. ACKERMAN, of Hohokus, Bergen county, State of New Jersey.

The object of our invention is to free the boots and shoes from dirt, dust, &c., with less trouble and more thoroughly than has heretofore been done. The annoyance and trouble appertaining to the freeing of boots and shoes from dirt, dust, &c., are felt by all. The cohesive nature of the dirt requires more than ordinary exertion to remove it. Our invention obviates all these difficulties and troubles by a simple device, which is easily constructed and built. It consists in placing upon a suitable frame two movable brushes, which are made to move by the upward and downward motion of the foot.

In order to more fully describe our invention, we will refer to the accompanying drawing.

Figure I is a side view of our invention. Fig. II is a plan of the same.

A represents the frame or stand, to which is attached, by hinge, another frame, B, which is held in an inclined position by the spiral spring C, but prevented from ascending too far by a guard, b, on the upright ratchet D, which is securely fastened to the frame or stand A by screws or other suitable means, and has a curved form, as represented in Fig. I. E is an axle, which has two wheels or cranks, I and J, fastened on its outer ends. On the center of this axle E is placed a cog-wheel, F, the teeth of the same fitting into the teeth of the upright ratchet D. G and H are two movable bars, having at their lower ends a groove, c, working on a pin, d, while the upper ends have rods e attached thereto, said rods working into rings f. By these devices the bars are held in their proper moving positions. Connecting these bars G H with the wheels I and J are two connecting-rods, K L. On the

inner sides of these bars G H are fastened two brushes, M and N. O is a stand for the foot to rest upon, supported by two legs, g and h, having spiral springs encircling them for the purpose of lowering and heightening the stand or foot-rest by aid of the foot itself. P represents a scraper, in order to remove the dirt under the boot.

To operate our invention the operator first places his foot upon the stand O. By pressing his foot upon it it will force the frame B downward. It is obvious in so doing that the cog-wheel F is passed down the upright ratchet D, thereby causing the cog-wheel to rotate. As it rotates it turns the wheels I and J, which, being connected with the bars G and H by connecting-rods K and L, force them to move alternately back and forth. Having the brushes attached thereto, these also move. The foot being in close contact with these brushes, it will be readily understood that by the force exerted by the backward and forward motion the brushes will remove the dust and dirt from the boots and shoes. By the assistance of the spiral spring C the frame or foot-rest is thrown upward of itself.

Having thus fully described our invention, we desire to claim—

The combination of the frames A and B, hinge a, spiral spring C, upright ratchet D with the guard b, axle E, wheels I and J, cog-wheel F, the bars G and H, groove c, pin d, rods e, rings f, connecting-rods K and L, brushes M and N, stand O, legs g and h, scraper P, substantially as and for the purpose hereinbefore set forth.

PETER O. TERHEUN.
JOHN I. ACKERMAN.
